UNITED STATES PATENT OFFICE.

ED MILLSAPS, OF LA FAYETTE, GEORGIA, ASSIGNOR OF ONE-HALF TO WILLIAM D. ATERS, OF ROCK SPRING, GEORGIA.

CENTRIFUGAL BRAKE FOR SPRING-MOTORS.

1,173,601.

Specification of Letters Patent. Patented Feb. 29, 1916.

Application filed July 15, 1915. Serial No. 40,052.

To all whom it may concern:

Be it known that I, ED MILLSAPS, a citizen of the United States, residing at La. Fayette, in the county of Walker and State of Georgia, have invented a new and useful 5 Centrifugal Brake for Spring-Motors, of which the following is a specification.

The present invention appertains to spring motors, and aims to provide a novel and improved mechanism for operating a churn, 10 ice cream freezer, cream separator, washing machine, sewing machine, coffee mill, and other devices.

One of the specific objects of the invention 15 is the provision of a spring motor having unique means for controlling the speed thereof.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed can be made within the scope of what is claimed, without departing from the spirit of the invention.

The invention is illustrated in the accompanying drawings, wherein:—

30 Figure 1 is a vertical section of the works. Fig. 2 is a sectional view illustrating the governor for controlling the speed of the machine.

In carrying out the invention there is 35 provided a works 3 which embodies a skeleton frame 4 through which is journaled the main shaft 5. An arbor 8 is journaled within the frame 4, and is connected by a gear train 9 with the main shaft 5, whereby the 40 shaft 5 is rotated much faster than the arbor 8. A spiral main spring 10 connects the arbor 8 and the gear train 9.

The governor for regulating the speed of the main shaft 5, embodies a shaft 15 journaled through the frame 4 near the shaft 5, and operatively connected thereto by means of a pinion 16 secured upon the shaft 15 and meshing with a relatively large gear wheel 17 secured upon the shaft 5. Thus, 50 the shaft 15 is rotated at a greater rate of speed than the shaft 5 so that the governor will be more effective or sensitive. A brake drum or wheel 18 is keyed upon the shaft 15,

and is inclosed by a circular case 19 attached to the frame 4, and a brake band 20 passes around the brake drum 18. One end of the 55 brake band 20 is anchored within the case 19, and the other end of the brake band is connected to a lever 23 fulcrumed to the frame. The lever 23 projects upwardly, in 60 order that it may be readily operated by hand. When the lever 23 is swung to tighten the brake band about the drum 18, the motion of the shaft 5 is stopped, and when the brake band 20 is loosened, the 65 mechanism is permitted to operate.

The governor embodies a pair of angular or L-shaped levers 25 having their elbows fulcrumed, as at 25^a, to the enlargement 15^a of the shaft 15, and one arm of each lever 70 25 is provided with a weight 26. The other arms 27 of the levers 25 are arranged to swing toward one another when the weights 26 are thrown apart by centrifugal action. A second pair of levers 28 are fulcrumed, as 75 at 29, to the shaft 15 adjacent the arms 27 of the levers 25, and are provided with diverging arms 30 between the arms 27 and lying in the paths thereof, whereby when the arms 27 move toward one another, the 80 arms 30 will be moved similarly. A coiled wire expansion spring 31 is disposed between the arms 30 for normally separating them and the arms 27. The arms 30 of the levers 28 are relatively short, and said levers 85 are provided with oppositely projecting relatively long arms 32 whose free ends project within a tapered or frusto-conical friction sleeve or cuff 33 which is lined with leather or other frictional material. The 90 smaller end of the sleeve 33 is secured to one end of an adjusting bar 34 which is slideable upon a pair of stems 35 which are attached to the frame 4, and coiled wire expansion springs 37 are disposed upon the 95 stems 35 between the bar 34 and the heads 36 of the stems, whereby the springs 37 will yieldably move the bar 34 away from the arms or brake shoes 32. An adjusting screw 38 is threaded through the frame 4 to bear 100 against the bar 34 between the stems 35, and projects so that it may be readily adjusted whenever desired.

When the shaft 5 is rotated, the shaft 15 will be rotated at a greater speed, and the 105 weights 26 will swing apart by centrifugal

action, causing the arms 27 to be moved toward one another. The arms 30 will therefore be swung toward one another, for separating the arms of brake shoes 32, and 5 when the arms 32 engage the interior of the sleeve 33, the speed of the machine will be checked. By adjusting the bar 34 through the medium of the adjusting screw 38, the sleeve 33 may be moved longitudinally relative to the arms 32, so that the arms will contact with the sleeve when the arms 32 are separated more or less. For example, when the sleeve 33 is arranged as illustrated in Fig. 2, the arms 32 may separate a comparatively large distance before contacting with the sleeve 33, whereas, if the sleeve 33 is moved over the arms 32, so that the arms 32 engage the smaller end of the sleeve, the arms 32 cannot separate but a short distance, and this will retard the motion of the machine to such an extent that it will rotate slower. By adjusting the screw 38, therefore, the speed of the machine may be controlled to a nicety.

Having thus described the invention, what 25 is claimed as new is:—

In a device of the character described, a shaft, a tapered sleeve movable upon said shaft, means for adjusting said sleeve, a pair of levers pivoted to said shaft and having 30 long arms projecting into said sleeve and providing brake shoes to contact with the interior thereof, said levers having relatively short diverging arms, an expansion spring between said short arms, and a pair 35 of L-shaped levers having their elbows fulcrumed to said shaft and having arms to bear against said short arms, and other arms provided with weights adapted to separate by centrifugal action.

In testimony that I claim the foregoing as my own, I have hereto affixed my signature in the presence of two witnesses.

ED MILLSAPS.
